UNITED STATES PATENT OFFICE.

GEORGE SIDNEY JEWETT, OF NORRIDGEWOCK, MAINE.

SELF-HEATING CAN.

No. 818,092.

Specification of Letters Patent.

Patented April 17, 1906.

Application filed June 19, 1905. Serial No. 266,066.

To all whom it may concern:

Be it known that I, GEORGE SIDNEY JEWETT, a citizen of the United States, residing at Norridgewock, in the county of Somerset and State of Maine, have invented certain new and useful Improvements in Self-Heating Cans; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to certain new and useful improvements in self-heating cans for canned goods; and it more specifically relates to improvements in that type of self-heating cans containing canned foods which are required before serving upon the table to be warmed or partially cooked, the can being adapted to heat or cook the contents by the action of slaking-lime contained within a compartment adjacent to or surrounding the compartment containing the food.

The invention has for its object to improve upon the constructions shown and described in Patents Nos. 720,434 and 720,435, granted to me February 10, 1903, whereby the can will be rendered more efficient and serviceable in use.

To this end and to such others as the invention may pertain the invention resides in the peculiar details of construction of the can, which will be hereinafter more fully described, shown in the accompanying drawings, and then specifically defined in the appended claim.

The invention is clearly illustrated in the accompanying drawings, which, with the letters of reference marked thereon, form a part of this specification, like letters of reference indicating like parts throughout the several views.

In the drawings, Figure 1 is a side elevation of my improved can with parts broken away. Fig. 2 is a central vertical section of the can. Fig. 3 is a top plan view of the receptacle.

Reference now being had to the details of the drawings by letter, A designates the outer can, which is made of tin or other sheet metal adapted to the purpose, the said outer can being of considerably greater size, both as to height and diameter, than the size of the ordinary or standard cans which are em-

ployed in packing canned foods, such as fruit and vegetables.

B is a fruit or vegetable can of the standard form and size and differing only from the cans commonly upon the market in that its head end, which is provided with the cap-covered filling-aperture C, is provided at its periphery with a slightly upward and outward extending flange portion D for a purpose which will presently appear.

The bottom end of the outer can A is provided with a central circular opening E, the diameter of which opening is slightly less than the diameter of the can B, and the periphery of this central opening E is provided with an inwardly-beveled flange e, the angle of inclination of the said flange e corresponding with the angle of the flange D upon the head end of the fruit-can B.

F is a shallow water pan or tray, which is constructed of suitable diameter as to permit it to be closely fitted in the upper end of the outer can A. The upper edge of the said pan or tray is bent at right angles to the vertical sides of the tray, thus forming a horizontal flange G, which extends slightly beyond the outer face of the body of the can and serves as a seat for the cover-plate H, which cover-plate is designed to be secured to the face of said peripheral flange, as will be understood.

The cover-plate H is provided near its outer edge with a circumferential depression or groove H', and within this circumferential groove or surrounded thereby is provided, in the face of the plate, a depression I to receive a puncturing-tool J, which is designed to be retained in the depression when not designed for use by a label pasted over the end of the can.

In assembling the parts of the can and preparing the same for use the fruit or vegetable can B is inverted and placed within the can A, and when properly placed the flange periphery D of the head of the can B will engage the flange e, surrounding the opening in the bottom of the outer can A, the engagement of these flanged surfaces serving to hold the can B securely against lateral displacement, as will be readily understood. After the can B has been thus placed in position within the outer can the space surrounding the inner can is filled with unslaked lime or its equivalent material, and the water-tray F, having first been filled with water, is seated within the upper end of the outer can, the depth of the said tray being such that when

it is seated it will bear directly upon the can B beneath it and will serve to hold the said can securely in place. The top plate H of the can A is then placed in position and cemented or otherwise suitably secured at its outer edge to the flanged upper edge of the water-tray.

When it is designed to cook or heat the contents of the can, the puncturing-tool J is removed from its seat by removing the label covering it, and with this tool an opening or several openings, if preferred, may be made within the groove H', the said openings extending through the cover-plate H and also through the bottom of the water-tray, thus permitting the water contained in the tray to enter the space surrounding the can B where it comes into contact with the lime or its equivalent material which is contained in said space. The slaking of the lime will within a few moments time serve to effectually heat or cook the contents of the can B.

The position of the groove or depression H' in the cover-plate H of the outer can A is essential, as it insures at all times that the puncturing of the bottom of the water-tray shall be at points directly above the space

containing the lime and prevents the liability of puncturing the can B.

Having thus described my invention, what I claim to be new, and desire to secure by Letters Patent, is—

A self-heating can, comprising an outer and inner receptacle with a space intervening between the same, the outer receptacle having a bottom with an annular groove in the upper surface thereof in which the inner receptacle fits, the portion of the bottom of the outer receptacle beyond said annular groove being inclined and bent to form an annular groove, adapted to receive the circumferential wall of the outer casing, a water-tank resting upon the top of said inner receptacle, a flanged top to said water-tank, having an annular groove therein, forming a shoulder and designed to hold said water-tank against the inner wall and flange of the outer receptacle, as shown and described.

In testimony whereof I hereunto affix my signature in the presence of two witnesses.

GEORGE SIDNEY JEWETT.
